Primary Examiner—Caron D. Veynar*Assistant Examiner*—Ricky Pham(74) *Attorney, Agent, or Firm*—Seth Natter; Natter & Natter(57) **CLAIM**

The ornamental design for a cooking device, as shown and described.

DESCRIPTION

FIG. 1 is a perspective view of a cooking device showing my new design;

FIG. 2 is a top plan view thereof;

FIG. 3 is a bottom view thereof;

FIG. 4 is a side elevational view thereof;

FIG. 5 is a front view thereof; and,

FIG. 6 is a perspective view of an alternate embodiment.

The side not illustrated is identical to the side illustrated in FIG. 4; the rear is identical to the front view of FIG. 5; the top, bottom, sides, front and rear of the alternate embodiment are identical to the respective views of FIG. 2, FIG. 3, FIG. 4 and FIG. 5, substituting circular apertures for the quadrilateral apertures.
